HENRI CHIREIX, OF PARIS, FRANCE

FREQUENCY-REGULATING SYSTEM

Application filed September 8, 1925, Serial No. 55,086, and in France September 10, 1924.

The present invention has as its object to provide means adapted to insure perfect regulation of the frequency of the currents generated by vacuum tubes, by arcs, or in a more general way by all auto-regenerator systems in which the frequency produced depends, in the last analysis, upon the electric constants or characteristics of the circuits.

10 Another object of the invention is to furnish in such a system particularly simple keying method.

The principle underlying the invention may be set forth as follows: The waves sent out by the generator to be regulated are heterodyned with a small auxiliary generator or heterodyne whose frequency may be regarded as perfectly stable. This auxiliary or standard generator may be constituted by 20 a vacuum tube of small size fed from batteries, a piezo-electric crystal, or any other source of constant high frequency currents connected with an oscillatory circuit, the assembly being safeguarded from outside influence by the aid of a Faraday cage.

By means of a first detector, beats of relatively low frequency are produced. These beats set up in a circuit, which is tuned or practically tuned, an alternating voltage 30 which is rectified by a second detector. The ensuing direct current is thereupon used in such a way as to cause the frequency of the main generator to differ from that of the auxiliary one by a constant value. If then the frequency of the latter is constant so also will be the frequency of the former.

One method of using this rectified current consists in causing it to saturate to a greater or less degree the iron core of a self-induction coil inserted in the circuit of the principal generator. Another method consists in using the rectified current to vary the characteristics of a vacuum tube connected in an appropriate manner to the circuit of the principal generator to vary the frequency of the latter in the correct sense. It can be readily seen that, regardless of the particular method used, a closed cycle is obtained through which the frequency of oscillations of the principal generator will differ by a

constant value from the frequency of the standard generator.

The frequency of the currents produced by the auxiliary or standard transmitter may moreover be changed by the use of a key or manipulator acting upon the said standard transmitter, to modify in a likewise constant manner the frequency of the main transmitter. What is thus obtained is the keying of the main transmitter by the method well known under the name of compensation-wave method.

The invention may be best understood from the following detailed description which should be read in connection with the accompanying drawing in which

Fig. 1 shows one modification conforming to the invention

Fig. 2 shows a detailed modification of certain circuits in Fig. 1 and Fig. 3 shows a further modification of the invention.

Referring to Fig. 1, the principal generator is represented at 20 and has in its output circuit a self-inductance 1 and condenser 2 together with the high frequency windings 3 of a saturated self-induction coil, of which 4 represents the primary windings through which passes a rectified direct current as hereinafter explained. These windings are so connected that the induced high frequency voltages subtract. The arrangement for such a saturated self-induction coil is well known and need not be further described. A constant frequency auxiliary generator or local heterodyne is shown at 5 which may consist of a vacuum tube oscillator, a piece of quartz possessing piezo electric properties and vibrating at mechanical frequency or any other form of constant frequency source. In the output circuit of the auxiliary generator are inserted the self-induction coils 6 and 7 of which 6 may be short circuited by the key 8 to cause a change in the frequency of the auxiliary transmitter or heterodyne. The coil 6 may of course be replaced by a condenser if desired. This generator is coupled through the coil 7 to an oscillatory circuit 9 preferably tuned to the mean frequency of the main transmitter and the auxiliary transmitter or heterodyne. 100

This oscillatory circuit receives energy from the generator 5 and the generator 20, causing a beat frequency therein. The beat frequency is first detected by a vacuum tube 11 having a shunted condenser 10 in its grid circuit and is then transferred by the coil 12 to the oscillatory circuit 13. This beat frequency is preferably chosen inside the range of audibility, say of an order of 5000 cycles per second. If the oscillatory circuit 13 is tuned to a higher frequency, say 6000 cycles, and conveniently damped an alternating potential will be set up across the common terminals of the condenser and self induction coil which is again detected by the tube 15 having in its grid circuit a shunted condenser 14. The plate circuit of the tube 15 contains the windings 4 which will therefore have rectified current flowing through them, whose value will be determined by the closeness of the beat frequency to the natural frequency of the circuit 13, that is if the beat frequency approaches the frequency of this circuit the current will increase and if the beat frequency recedes from the frequency of this circuit the current will decrease. The coils 4 are shunted by condenser 16 which has the effect of attenuating the fluctuations of the rectified current and preventing at the same time all reactive effects of the circuit 1-2-3 on the tube 15.

A numerical example may be cited to better grasp the operation. Suppose that currents or waves of a frequency of 3,000,000 cycles are to be transmitted. Then the auxiliary generator 5 will have to be regulated so as to produce a frequency of 3,005,000 cycles giving the main self-induction coil 1 a value such that under these conditions there is effectively obtained a frequency of 3,000,000 cycles. If the damping of the circuit 13 is conveniently chosen, this working condition will correspond to a mean direct current in the windings 4 (with a certain margin either way).

It will furthermore be seen that, if for some reason or another, the frequency of the main generator has a tendency to increase, the beat frequency will have a tendency to decrease, consequently also the current in the circuit 13, and the direct current in the plate circuit of the detector 15. And as the direct current tends to decrease, the saturation also shows a tendency to fall off, and as a consequence the inductance of the saturated self-induction coils tend to increase in value which prevents the main oscillator from growing in frequency. The developments are just the contrary of what has been stated whenever there is a tendency for a drop in frequency. In view of the fact that mechanical inertia is wholly absent, and that the time-constants of the various circuits can be made very low, the regulation takes place instantaneously.

Fig. 2 illustrates a somewhat improved arrangement. 12' corresponds to 12 in Fig. 1 and acts as a primary of the transformer whose secondary 13' works upon a tuned shunt 14' 15'. The space between grid and filament in detector 17' is taken to the terminals of the entire tuned shunt, whereas the space between the plate and the filament is brought to the terminals of the self-induction coil 14' or the capacity 15' (as shown in the figure). The windings 4' of the saturated self-induction coil correspond to the windings 4 of Fig. 1. It will be readily seen that the operation is the same, but if in this case the curve of the detected direct current as a function of the frequency applied at 12' is plotted, it will be found that this graph is a straight line about the natural frequency of the tuned shunt, whereas in the case of Fig. 1 there is found a curve with a downward concavity. This circumstance is evidently due to the fact that below the resonance frequency, the grid and the plate potentials are co-phasal, and that beyond the said point they are, on the contrary, in phase opposition. Nothing of that kind is present in the case of Fig. 1 where the plate potential is furnished by the cell 18. This offers a certain advantage; as a matter of fact, the auxiliary transmitter can be so regulated that the beat frequency is made equal to the natural frequency of the oscillating shunt whereas in the case of the arrangement in Fig. 1 it is necessary to keep on one side thereof, whereby greater sensitivity is realized, while yet preserving a stable working condition.

The saturated self-induction coils shown in this arrangement are of extremely small volume or size. Bearing in mind that a tube transmitter outfit, even if no special precautionary means and measures are adopted, insures a stability in frequency of 1/1000, it will be clear that the variation of the self-inductance attains 1/1000 of the self-inductance 1 hence, the variation in reactive power stored up in this self-induction coil should not be more than 1/1000 the total reactive power.

Before proceeding to the description of the modification in Fig. 3 it should be fixed in mind that the invention as thus far described comprises two essential parts, the first feature relating to the production of a current with an amplitude varying very rapidly with the frequency, while the second characteristic covers the utilization of this current in a saturated self-inductance coil.

The embodiment shown in Fig. 3 discloses improvements upon both of the main characteristics of the invention. More particularly speaking, the beat current obtained after the first detection is amplified by an amplifier arrangement of any desired type and comprising a plurality of stages if desired.

Moreover, in lieu of a simple resonant or 5 tuned circuit (as shown in Fig. 1) a filter comprising several stages is used, this arrangement presenting the advantage of increasing the selective properties of the circuit in far greater proportion than the time constant.

The second detection is furthermore effected in a particular manner by having recourse to the beat currents for wholly or partially supplying the energy required for the heating of a valve, in such a manner that when the amplitude of the beat currents increases, the thermionic emission of the valve 10 in question grows very rapidly. In virtue of such extremely rapid growth in thermionic emission as function of the temperature, there results an equivalent increase in tuning and resonance.

Referring now to the diagram in Fig. 3, 15 33 represents the main oscillator and 21 represents the auxiliary constant frequency generator or heterodyne. The frequency of the heterodyne is combined as before with the frequency of the principal generator to obtain 20 a beat frequency, which passes through a detector 22. The output of the detector 22 is amplified by the multi-stage amplifier 23 and impressed on a filter 24 which is analogous 25 in its operation to the circuit 13 in Fig. 1. The output of this filtering circuit is amplified by the tube 25 and impressed on a transformer 26 whose secondary serves to energize the filament of the two-electrode valve 27. A battery 28 may be used in series with 30 this secondary to assist in the energizing action if desired. The electron-emission of valve 27 is thereby controlled by the current in the secondary of the transformer 26 and the value of this current depends on the 35 beat frequency formed by heterodyning the output of generator 33 with the constant heterodyne 21. The valve or detector 27 will serve to transfer the alternating current of 40 variable amplitude into a direct current which is also of variable amplitude. This direct current is impressed across the resistance 30 in parallel with the filament grid circuit of a vacuum tube 31, a battery 29 being provided in the output circuit of detector 27 to overcome the drop in the tube 45 and the drop in the resistance 10. The tube 31 acts as a variable resistance and has its plate filament circuit connected across the condenser 32 in the grid circuit of the generator 33. This plate circuit also includes choke coils 35. The principal generator 33 50 may be energized in any desired manner, a coil 34 representing the energizing means in the present case.

The operation of this system will be readily understood. If the frequency of the principal generator undergoes a slight change the current supplied at the end of the filter 55 24 varies in amplitude, the temperature of the

filament of valve 27 changes and in consequence the electron-emission of the valve undergoes considerable variations. These variations cause a great modification in the potential applied at the grid of tube 31 and therefore corresponding modifications in the resistance of the plate-filament of this tube. These last modifications in turn result in a variation in the main potential in the grid of oscillator 33 causing variations in the frequency produced, such variations being of such a sense that they tend to correct the original variations which have given rise to them.

While I have disclosed the invention in several specific modifications it will be obvious that many modifications will readily occur to those skilled in the art, for example, the heterodyne generator may be caused to interfere with the harmonics or overtones of the wave sent out by the principal generator instead of causing it to interfere directly with the fundamental wave.

The rectified current of variable amplitude may likewise be used for other purposes than the one of saturating an iron core choke coil or of varying the electron emission of the valve rectified. It could be used as well to excite a dynamo whose potential could be applied in the plate circuit, in the grid circuit or in the heating circuit of the three electrode generator tube. I intend to be limited therefore only as indicated by the scope of the following claims.

Having described my invention, I claim:

1. A constant frequency generating system, comprising an oscillation generator and a constant frequency heterodyne arranged to beat therewith for producing a beat frequency, an oscillatory circuit tuned to said beat frequency, rectifying means associated with said beat frequency circuit, and frequency compensating means included in the generator output circuit controlled by the rectified beat frequency currents for affecting a constant relationship between the heterodyne constant frequency and the generator frequency.

2. A system for generating high frequency currents of a desired constant frequency, comprising an oscillation generator, a local heterodyne for beating with the generated frequency, a circuit tuned to said beat frequency, rectifying means for producing a direct current proportional to the beat frequency, said beat frequency varying with variations in the generated frequency, and means controlled by a change in rectified beat frequency current for affecting a change in the electrical characteristics of the frequency controlling circuit of the generator to preserve the desired frequency.

3. In a frequency control system, an oscillation generator and a local heterodyne arranged to beat therewith for producing a

beat frequency, an oscillatory circuit tuned to said beat frequency, a detector associated with said tuned circuit for producing rectified direct current in its output circuit proportional to said beat frequency, and means associated with the generator and detector output circuits whereby any change in the rectified current caused by a change in beat frequency which in turn is caused by a variation in the generated frequency will produce a corresponding change in the generator output to preserve the desired frequency.

4. A constant frequency generating system, comprising a main oscillator and an auxiliary oscillator arranged to beat therewith for producing a beat frequency within the audible range, a circuit tuned to said beat frequency, rectifying means associated with the tuned circuit for producing a direct current proportional to the beat frequency, said beat frequency varying inversely with variations in the main oscillator frequency, and an iron-cored inductance inserted in the frequency determining circuit of the main oscillator adapted to be saturated to a greater or less degree by the rectified direct current to alter the inductance and to thus compensate for any change in the main oscillator frequency.

5. A constant frequency generating system, comprising an oscillation generator subject to slight variations in frequency, a constant frequency heterodyne arranged to beat therewith for producing a beat frequency, a first detector having its input circuit tuned to said beat frequency, a second detector associated with the output of said first detector and having its input circuit tuned to a frequency differing from the beat frequency, and frequency compensating means included in the frequency controlling circuit of the generator controlled by the rectified current in the output circuit of the second detector for maintaining the generated frequency substantially constant.

6. A constant frequency generating system, comprising an oscillation generator subject to slight variations in frequency, a constant frequency heterodyne arranged to beat therewith for producing a beat frequency within the audible range, a first detector having its input circuit tuned to said beat frequency, a second detector having its input circuit tuned to a frequency higher than the beat frequency and coupled to the output of the first detector, and frequency compensating means connected in the generator output and controlled by rectified current in the output circuit of the second detector for maintaining the generated frequency substantially constant, the magnitude of the controlling rectified current depending upon the difference between the beat frequency and the frequency to which the input circuit of the second detector is tuned.

7. The method of maintaining the fre-

quency of a high frequency generator substantially constant, which consists in heterodyning the generator output to produce a beat frequency which varies with accidental variations of the desired generated frequency, detecting said unstable beat frequency, then causing the resulting detected current to affect a compensating change in the electrical characteristics of the generator output to preserve the desired generated frequency.

8. The method of maintaining the frequency of a vacuum tube generator substantially constant, which consists in suitably heterodyning the generator output to produce a beat frequency within the audible range, said beat frequency varying inversely with accidental variations of the desired generated frequency, detecting said varying beat frequency, then causing the rectified currents due to changes in beat frequency to affect a compensating change in the generator output by altering the electrical characteristics thereof to preserve the desired generated frequency.
